DESIGN FOR A BIER

Earl C. Babcock, Painesville, Ohio

Application February 2, 1937, Serial No. 67,402

Term of patent 3½ years

To all whom it may concern:

Be it known that I, Earl C. Babcock, a citizen of the United States, residing at Painesville, in the county of Lake and State of Ohio, have invented a new, original, and ornamental Design for a Bier, of which the following is the specification, reference being had to the accompanying drawing, forming a part thereof.

Fig. 1 is a front elevational view of a bier showing my new design in position for use;

Fig. 2 is a top plan view of the bier illustrated in Fig. 1.

Fig. 3 is a right end elevation of the bier illustrated in Fig. 1; and

Fig. 4 is an enlarged view taken along the line 4—4 in Fig. 1.

I claim:

The ornamental design for a bier as shown.

EARL C. BABCOCK.
